UNITED STATES PATENT OFFICE.

FOSTER E. WORTLEY, OF MAPLEWOOD, NEW JERSEY, ASSIGNOR TO NEW YORK WIRE
& SPRING COMPANY, A CORPORATION OF NEW JERSEY.

AUTOMOBILE BUMPER.

Application filed October 26, 1925. Serial No. 64,794.

This invention relates to improvements in automobile bumpers.

One of the objects of this invention is to produce a bumper embodying a novel member of enhanced ornamental appearance and to mount the same in a bumper in a manner which will fully display the attractive ornamental appearance of one or more of such impact members and will cause the bumper to have a finished appearance, particularly around the opposite ends of said impact members.

Another object of the invention is to provide an impact bar having inherent resilience with a thin ornamental strip of metal of contrasting color and to utilize the inherent resilience of the said impact bar to procure a tight retention of such strip on the said bar intermediate the ends thereof without the use of rivets, bolts or the like which would mar the appearance of such ornamental strips intermediate the ends of such bars.

Another object of the invention is to provide an impact bar in which the ornamental strip will be tightly retained on the bar by such inherent spring power around curved or looped end portions thereof and thus to improve the appearance of the bar at said end portions.

Still another object of the invention is to produce an extended area bumper formed of a plurality of such bars without passing any rivets, bolts or the like through such strips or bars so as to avoid marring the said strips and to maintain a greatly improved ornamental appearance between the ends of said bars and at the curved ends thereof, also to avoid the use of unsightly rivets between the ends of the bars; also to add to the durability of the bars, and to avoid places on such bars where corrosion is likely to occur.

Still another object is to provide an extremely simple method of attaching ornamental strips to bumper bars with a minimum amount of time and labor.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form

illustrated in the accompanying drawings, in which:

Fig. 1 is an elevation of the parallel bar bumper embodying my invention;

Fig. 2 is a plan view of the bumper shown 60 in Fig. 1;

Fig. 3 is a plan view of a bar reversely bent to enable the attachment at opposite ends of the ornamental inlaid strip;

Fig. 4 is a similar plan view showing the 65 bar in its normal bowed position with the thin ornamental strip securely and tightly held in place by the inherent resilience of the bar;

Fig. 5 is a section on the line 5—5 of Fig. 70 6 looking in the direction of the arrow;

Fig. 6 is a section on the line 6—6 of Fig. 5 looking in the direction of the arrow, and

Fig. 7 is a section on the line 7—7 of 75 Fig. 1.

Referring now to these drawings which illustrate a preferred embodiment of my invention, 10, 10 indicate a pair of impact bars each comprising a spring steel bar of suitable thickness and a length which will cause it to extend transversely across the chassis and wheels of an automobile. Each of the impact members 10, 10 is provided on the front face thereof with a shallow groove preferably having inlaid or fitted in 80 said groove and securely and tightly fastened to the bars, a thin ornamental metal strip 11 which is preferably colored to contrast with the color of the bar portions on opposite sides of the groove and may be 85 plated or polished thus producing an ornamental effect.

In accordance with my invention this thin-metal ornamental strip is connected to the bar only at the end portions thereof and is 95 held securely in place within the groove in said bar intermediate the ends thereof without the use of rivets or other fastening devices which would not only mar the ornamental effect of the mounting of the inlaid strip but would provide cracks and joints which are likely to corrode and thus further 100 to detract from or mar the appearance and durability of the bar. This tight or hugging connection is accomplished with a minimum amount of time and labor by utilizing the inherent resilience of the spring bar for the purpose of tightly retaining the said strip within the grooves intermediate the 105 said ends. Thus the bar is reversely bowed 110

as indicated in Fig. 3 so as to shorten the distance between the ends thereof. A thin ornametal strip 11 of proper length is then connected by rivets 12 to the opposite extremities only of the bar 10, the said strip 11 passing around the curved or looped ends 13, 13' of the said bar, after which the bar 10 is allowed gradually to assume its normal outwardly-bowed position as indicated 10 in Fig. 4. In this position the strip will fit within the groove and be tightened and retained against the surface thereof by the inherent resilience of the bar and an impact member of enhanced ornamental appearance 15 will be produced. Furthermore, the fastening of the ornamental strip to the bar will be substantially concealed from view around the looped or curved ends thereof and these ends as well as the middle portion of the 20 bar will present a finished ornamental appearance and will cause a bumper in which the bar is embodied to have an enhanced ornamental and finished appearance.

In the preferred embodiment of my invention, a pair of such ornamental bars 10 having inlaid strips 11 so attached are held between their end or looped portions by clamps 14, 14 each of which abuts against the front faces of the two bars and lock the same in place without the passing of rivets or the like through the said ornamental strips or through the bars themselves. End clamps 15, 15 are employed for the ends of the said two bars 10. These end clamps, however, are each provided with an extension 15^a which abuts against the rear surfaces of said impact bars and also clamps to the double impact bars single rear bars 17 by bolts 16, which rear bars 17 are preferably reversely curved to form loops 18 and have their free ends 19 engaged by the intermediate clamps 14. These rear bars are connected intermediate their ends with conventional bracket bars 20 which are suitably fastened to the chassis of the car in any suitable manner not shown.

Having described my invention, I claim:

1. An impact bar for automobile bumpers embodying a resilient bar, an ornamental strip fastened to said bar at the opposite ends only and retained intermediate said ends in tightened contact with said bar by the inherent resilience thereof.

2. An impact bar for automobile bumpers 55 embodying a resilient bar provided on its front face with a groove, an ornamental strip inlaid within said groove and fastened to said bar at the opposite ends only and retained intermediate said ends in tightened 60 contact with said bar by the inherent resilience thereof.

3. An impact bar for automobile bumpers comprising a bar of resilient metal provided with looped ends, a thin strip of ornamental metal fastened to said bar at the terminal portions thereof and extending around the said looped ends, said strip being tightly retained on the face of said bar by the inherent resilience thereof. 70

4. A bumper comprising a plurality of impact bars each comprising a bar of resilient metal having a thin strip of ornamental metal fastened thereto at the opposite ends thereof only, said strip being held intermediate the ends of said bar by the inherent resilience of the metal thereof and said bar and strip being imperforate between said end fastenings, and clamping means for mounting said plurality of bars to form 80 a bumper of extended impact areas, said clamping means having engagement with the outer surfaces only of said imperforate bars. 75

5. The process of attaching ornamental 85 strips of metal to impact bumper bars of spring metal consisting in bending the spring metal bar in reversed direction, attaching the ornamental strip at opposite ends to said bar while so reversely bent and 90 then to permit said bar to assume its normal position and to retain said strips in contact against the same by the inherent resilience thereof.

6. The process of attaching ornamental 95 strips of metal to impact bumper bars of spring metal consisting in bending the spring metal bar in reversed direction to reduce the distance between its ends, attaching the ornamental strip at opposite ends 100 to said bar while so reversely bent and then to permit said bar to assume its normal position and to retain said strips in contact against the same by the inherent resilience thereof. 105

In witness whereof, I have signed my name to the foregoing specification.

FOSTER E. WORTLEY.
